DESIGN FOR A CHAIR

Willard H. Bond, Jr., East Grand Rapids, Mich.,
assignor to American Seating Company, Grand Rapids, Mich., a corporation of New Jersey

Application June 28, 1935, Serial No. 57,448

Term of patent 7 years

To all whom it may concern:

Be it known that I, Willard H. Bond, Jr., a citizen of the United States, residing at 605 Greenwood St., East Grand Rapids, in the county of Kent and State of Michigan, have invented a new, original, and ornamental Design for a Chair, of which the following is a specification, reference being had to the accompanying drawing, forming a part thereof, in which:—

The figure is a perspective view of a chair, the distinguishing, essential and dominating feature or characteristic of the design being the end standards of the chair shown in full lines, the form and contour of the back, seat and arm rests being shown in dotted lines and indicating unimportant features of the design.

I claim:

The ornamental design for a chair as shown and described.
